UNITED STATES PATENT OFFICE.

ELMER E. SEELEY, OF CONNEAUTVILLE, PENNSYLVANIA.

FLUID-INDICATOR.

1,061,874.

Specification of Letters Patent.

Patented May 13, 1913.

Application filed June 4, 1912. Serial No. 701,595.

To all whom it may concern:

Be it known that I, ELMER E. SEELEY, a citizen of the United States, residing at Conneautville, in the county of Crawford and 5 State of Pennsylvania, have invented new and useful Improvements in Fluid-Indicators, of which the following is a specification.

The invention relates to fluid indicators, 10 and more particularly to the class of combined fluid strainers and indicators.

The primary object of the invention is the provision of a device of this character in which fluid within a container can be measured 15 so as to determine the quantity or the level thereof within the container.

Another object of the invention is the provision of a device of this character wherein fluid when being introduced into a container 20 will be strained so as to render it free from foreign matter, thereby avoiding the accumulation of sediment or foreign matter interiorly of the container.

A further object of the invention is the provision of a device of this character wherein in the indicator guide tube may be detachably fitted within the inlet opening in a container and the closure for the latter connected therewith, thus obviating the necessity 30 of forming a separate aperture for receiving the device or requiring alteration in the construction of the container or those ordinarily used.

A still further object of the invention is the provision of a fluid strainer and indicator which is adapted to be detachably fitted within a fluid tank of that class generally employed in connection with automobiles, motor boats or other self-propelling 40 vehicles, so that on filling the receptacle the fluid may be strained and also the quantity accurately measured when held within the receptacle.

A still further object of the invention is the provision of a device of this character in which the length may be increased or decreased so as to admit it to fit fluid containers of varying depths, whereby the fluid therein can be measured for determining the 50 quantity or level thereof.

A still further object of the invention is the provision of a device of this character which is simple in construction, reliable and efficient in its purpose, and inexpensive in 55 manufacture.

With these and other objects in view the

invention consists in the construction, combination and arrangement of parts as will be hereinafter more fully described, illustrated in the accompanying drawing, and pointed out in the claims hereunto appended.

In the drawing:—Figure 1 is a fragmentary vertical sectional view through a fluid container showing the combined strainer and indicator constructed in accordance with the invention mounted therein. Fig. 2 is a vertical longitudinal sectional view through the device. Fig. 3 is a perspective view of the cap used with the indicator.

Similar reference characters indicate corresponding parts throughout the several views in the drawing.

Referring to the drawings by numerals, 5 designates a portion of a body of a fluid receiver which may be of any ordinary well-known construction, and is designed more especially for use in automobiles, motor boats, or other self-propelled vehicles, the body being formed with the usual internally threaded filling opening for receiving a cap 30 6 which latter is adapted to be removed so that the tank may be filled by the pouring of fluid through the opening in the body thereof.

Adapted to be inserted through the 35 threaded opening in the body 5 of the tank is a combined fluid strainer and indicator comprising a cap 7 formed with a central opening 8 and also provided with an externally threaded flange 9 which is of less size 90 than the circumferential area of the major portion of the said cap 7 and is designed to detachably engage in the internally threaded opening in the body 5 of the tank for the mounting of the said cap therein, after the 95 screw cap 6 has been detached from the said tank. The cap 7 is formed with an internally threaded annular wall 10 for permitting the screw cap 6 to be engaged therein, so that it may be carried thereby.

Fixed to or integral with the flange 9 of the cap 7 is the inner section 11 which adjustably telescopes within the outer section 12 of a tubular guide, the outer section 12 being formed with a closed bottom 13, while the side wall thereof is provided at intervals with vertically alining outlet openings 14, whereby on the pouring of fluid into the guide the same will discharge through the outlet openings 14 into the body 5 of the tank for the filling thereof. Fixed to the inner face of the side wall of the outer sec-

tion 12 and spanning the outlet openings 14 is a foraminous strainer strip 15 preferably constructed from wire mesh fabric so that the fluid flowing from the guide into the body of the tank will be thoroughly strained for removing all foreign matter therefrom, thereby avoiding the accumulation or settlement of foreign matter interiorly of the tank, it being understood of course that the fluid is introduced into the guide through the central opening 8 in the cap 7, whence the fluid will pass through the strainer strip 15 and openings 14 into the body of the tank for the filling of the same.

15 Loosely positioned within the tubular guide is a float 16 constructed of suitable buoyant material preferably cork, and secured to this float is a vertically projecting measuring rod 17, the same being provided 20 with suitable graduations 19 and has its upper end projected through the opening 8 in the cap 7, so that the said rod at its upper end will abut against the screw cap 6 when engaged in the cap 7 and in this manner 25 held from rising within the tubular guide. However, on the removal of the cap 6 from the cap 7 the rod 17 will instantly elevate within the tubular guide by reason of the pressure of the fluid within the tank 5 against the float 16, so that on the projecting of the rod exteriorly of the tank the 30 graduations thereon will be clearly visible for the reading of the same to accurately determine the quantity or the level of the fluid within the tank, it being understood of course that when it is desired to fill the tank the rod 17 and its float 16 are removed from the tubular guide and the fluid is introduced through the central opening 8 into the guide 40 in a manner as heretofore described.

It is of course understood that when the inner and outer sections 11 and 12 of the tubular guide are adjusted, so as to increase the length of the latter whereby the said 45 guide may be placed within tanks of varying depth a measuring rod 17 of the required length will be fixed within the cap 7 in proper working position in the tubular guide for measuring purposes. In other 50 words, when the tubular guide is shortened

a measuring rod 17 is substituted for the 55 measuring rod, it being understood of course that the substituted measuring rod is of a length corresponding to the length of the tubular guide when adjusted.

From the foregoing description, taken in connection with the accompanying drawing, it is thought that the construction and operation of the invention will be clearly understood, and therefore, a more extended explanation has been omitted.

What is claimed is:—

1. A device of the class described comprising a sectional extensible tube guide, a measuring element movably mounted therein, one of said sections of the guide being provided with perforations, and a foraminous strainer strip covering the perforations. 65

2. The combination with a fluid container 70 having a filling hole and also having a cap for the latter, of a device comprising a sectional extensible tube guide, a measuring element movably mounted therein, one of said sections of the guide being provided with 75 perforations, a foraminous strainer strip covering the perforations and means for suspending the said guide from the filling hole of the fluid container and adapted to receive the cap. 80

3. The combination with a fluid container having a filling hole and also having a screw cap for the latter, of a device comprising a sectional extensible tube guide and having perforations, a measuring element 85 therein, a foraminous strainer strip covering the perforations, means for suspending the said guide from the filling hole of the fluid container and adapted to receive the screw cap, one of said sections being telescoped within the other of the guide and adapted to permit longitudinal adjustment of the latter. 90

In testimony whereof I affix my signature in presence of two witnesses.

ELMER E. SEELEY.
